Attorney

UNITED STATES PATENT OFFICE.

ARTHUR C. HOPKINS, OF SIOUX FALLS, SOUTH DAKOTA, ASSIGNOR OF ONE-HALF TO
THERON R. BEMENT, OF SIOUX FALLS, SOUTH DAKOTA.

ATTACHMENT FOR INTERNAL-COMBUSTION ENGINES.

1,221,536.

Specification of Letters Patent.

Patented Apr. 3, 1917.

Application filed June 2, 1916. Serial No. 101,317.

To all whom it may concern:

Be it known that I, ARTHUR C. HOPKINS, a citizen of the United States, residing at Sioux Falls, in the county of Minnehaha and State of South Dakota, have invented certain new and useful Improvements in Attachments for Internal-Combustion Engines, of which the following is a specification.

- 10 This invention relates to an attachment for internal combustion engines, and has for its principal object to provide a device for conducting heated air from the exhaust manifold to the intake manifold for the purpose of economizing liquid fuel and for increasing the efficiency of the engine, and for preventing carbon deposits, and which may be used effectively during hot or cold weather.
- 15 Other objects relate to the provision of such a construction that the parts required will be few, may be conveniently manufactured, and will be adapted to sustain the vibration and stresses incident to its use and 25 will not be injured by exposure to the high degree of heat to which it may be subjected.

The invention includes the employment of parts having such form and arrangement that adjustments thereof may be conveniently and readily made for a complete control of the movements of heated air, and a control of suction in conjunction with the operation of the carburetor; and also includes novel and useful means for housing 35 and utilizing the heat from the exhaust manifold.

With the foregoing objects in view and others to be mentioned, the invention presents a novel construction, combination and 40 arrangement of parts as described herein and claimed, and as illustrated in the accompanying drawing, wherein,—

Figure 1 is a view, partly broken and in section, showing the device applied to the 45 exhaust manifold and intake manifold. Fig. 2 is a view in side elevation of a barrel member or tubular housing for the valve and valve casing. Fig. 3 shows the ball valve. Fig. 4 is a side view of the valve casing. Fig. 5 is an end view of the valve casing. Fig. 6 is a transverse section on line 6 6 of Fig. 4. Fig. 7 is a view showing the inner side of the heat-receiving receptacle for the exhaust manifold. Fig. 8 is a side view of 55 parts, showing the device when mounted,

said view being broken and on a reduced scale. Fig. 9 is a sectional view on line 9 9 of Fig. 7.

Referring now to the drawing, I provide a housing member 11, consisting of a tube 12 60 interiorly threaded at its open end for a mounting upon the nipple 22, its opposite end being closed to provide a head piece 13 so that the valve casing 14 may be adjusted longitudinally thereof, the tubular housing 65 12 being provided, to open on one of its sides adjacent to the head piece, with a collar 15, said collar providing an intake port for and preferably being disposed substantially at right angles to the axis of said 70 tubular housing.

The valve casing 14 is of cylindrical form, and is provided on its outer side, near its open end, with an annular groove 16, within said groove being disposed a packing ring α 75 of asbestos or similar material which will not be injured by action of heat, the outer, imperforate end of said valve casing being provided with a threaded stem 17 which is adapted to traverse the head 13, centrally, 80 and to have a threaded connection therewith.

The wall of the valve casing is provided with apertures 18 having an inclination outwardly toward the imperforate end of said 85 valve casing, so that the heated air, while moving, will not be unduly obstructed, but will be thoroughly mixed before entering the intake manifold.

A ball valve is indicated at 19. It is 90 adapted to have a seating in the concaved recess 20 of the valve casing and to be pressed upon its seat, normally, by action of the coiled spring 21, said spring being disposed in the tubular housing with its respective ends abutting upon said valve and the nipple 22, said nipple having a threaded connection with one of the walls of the intake manifold 23, comparatively remote 95 from the carburetor (not shown) and, preferably, bear the branches α of said intake manifold, said nipple being provided at its discharging end with a projecting part or ledge β nearest to the incoming gas from the carburetor, and operating as a deflector or shield, so that the heated air, from the tubular housing may move freely within the intake manifold, and that its movement, as indicated by the arrows in the drawing, 100 will not be unduly impeded. 110

Numeral 24 indicates a heat-receiving receptacle consisting of an attenuated plate *c* bent substantially to the surface conformation of the exhaust manifold 25, upon which it is mounted. It is provided with side walls *d* for the purpose of conserving the heat, and for being maintained in spaced relation or adjacent to the wall of the exhaust manifold.

Any suitable means may be provided for maintaining the walls *d* of the receptacle 24 in contact with the exhaust manifold, the means herein shown for this purpose being the bands 26. The side walls *d*, in conjunction with the plate *c* provide a housing space, compartment or receptacle for temporarily receiving or containing the heat produced, and at *e* are indicated recesses formed in the walls *d* and which open upon the edges of said walls, for admitting air to be heated by exposure to the surface of the exhaust manifold.

Numeral 27 indicates a pipe of any suitable length having its respective ends mounted upon the collar 28 of the receptacle 24 and upon the collar 15, by means of which the heated air may be conducted from said receptacle 24.

By means of the construction described, air which is practically void of moisture and which has a high degree of heat may be provided for the intake manifold, and by action of suction may pass the valve subject to the resistance of the spring 21. While the air may not be of uniform temperature in the compartment 24 or pipe 27, it will become thoroughly mixed when passing through the apertures 18 of the valve casing.

On account of the different kinds of carbureters used for internal combustion engines, the dry or moist climates where used, and the hot and cold weather when used, it will be appreciated that the means for adjustments mentioned is an important feature, for operation. By means of the threaded stem 17 the valve casing may be rotated conveniently for a movement longitudinally of its tubular housing for compressing or retracting the spring, with the

result that air may pass the valve with slight resistance to the intake manifold, or the air may be wholly prevented from passing therethrough, and therefore the device, which may have any desired size or proportion, is adapted for general use, and may be applied to the exhaust and intake manifolds of any engine of the class described.

Having fully described construction, a further explanation relating to operation is not necessary.

What I claim and desire to secure by Letters Patent is—

An attachment for internal combustion engines, including an exhaust-manifold and an intake-manifold, a receptacle conformable to the exterior of said exhaust-manifold, with air-inlets in its side-walls, the inner edges of the walls of said receptacle being in contact with said exhaust-manifold thus providing a space or chamber between the receptacle and this latter, means for the retention of said receptacle upon the latter, a tubular housing in communication with said intake-manifold, a spring-pressed valve, a valve-seat forming tubular member having ports adapted to provide for the passage of heated air into said tubular member; said seat-forming tubular member being positioned within said tubular housing and slideable therein, said valve being held upon its seat by its pressure-applying spring, said valve-seat forming tubular member having an annular groove containing a packing for fitting the valve-seat tubular member fluid tight within said housing, means for adjusting the position of said valve-seat forming tubular member adapted to provide for controlling the tension of said spring, and a tubular member effecting connection between said receptacle and said tubular housing.

In testimony whereof, I have affixed my signature in presence of two witnesses.

ARTHUR C. HOPKINS.
